The ornamental design for a sign display, as shown and described.

DESCRIPTION

FIG. 1 is a frontal elevation view showing a first embodiment of our new design for a sign display of the present invention.

FIG. 2 is a right side elevation view of the sign display of the first embodiment thereof.

FIG. 3 is a left side elevation view of the first embodiment thereof.

FIG. 4 is a frontal elevation view showing a second embodiment of the sign display of the present invention with break lines indicating no specific length.

FIG. 5 is a right side elevation view of the second embodiment thereof, with break lines indicating no specific length.

FIG. 6 is a left side elevation view of the second embodiment thereof, with break lines indicating no specific length.

FIG. 7 is a top elevation view of the first and the second embodiments thereof.

FIG. 8 is a bottom elevation view of the first and the second embodiments thereof; and,

FIG. 9 is an isometric view of the second embodiment of the sign display thereof, with break lines indicating no specific length.

The present invention is a sign display for changeable signs that can be placed and replaced behind a transparent block so as to be displayed.
